PORTABLE STRAP DISPENSER

Michael O. Derrickson, Norwood, Pa., assignor to FMC Corporation, Philadelphia, Pa., a corporation of Delaware

Filed June 9, 1964, Ser. No. 80,339

Term of patent 14 years

(Cl. D41—1)

FIG. 1 is a side elevational view of a portable strap dispenser showing my new design.

FIG. 2 is a rear elevational view;

FIG. 3 is a front elevational view; and

FIG. 4 is a top plan view.

In FIG. 1 the chain dotted lines indicate the strapping material which is shown for purposes of illustration only.

I claim:

The ornamental design for a portable strap dispenser, as shown and described.
